TERMINAL FOR ELECTRICAL CONDUCTORS

Jesse M. White, Philadelphia, Pa.

Application August 11, 1938, Serial No. 224,294

2 Claims. (CL. 173—269)

This invention relates to terminals for electrical conductors and is concerned primarily with the affixing of a terminal to an insulated electrical conductor by crimping operations.

5 This application is a continuation in part of my copending application, Serial No. 60,917, filed January 27, 1936, entitled "Terminal for electrical conductors."

10 At the present time the use of insulated electrical conductors having terminals affixed to their extremities is becoming more and more widespread, particularly throughout the automotive industry, in that the manufacture of every motor vehicle involves a large number of detachable connections, the connections usually consisting of a socket in which is received a terminal that is affixed to the extremity of the conductor. Due to the fact that every time the connection is to be broken a pull is exerted on the conductor there 15 20 25

20 is a grave tendency for the connection between the terminal and the conductor to be destroyed, and this tendency has been harmfully felt in the automotive field under conditions of actual service usage, and now known methods of affixing the terminals to the conductors.

From the viewpoint of holding to a minimum the cost of assembling the terminals on the conductors it is well recognized that the most desirable method of affixing the terminals on the 30 35 40 45 50

30 conductors is by so-called crimping operations, which involve a simultaneous deforming of the metal of the terminal and the conductor therewithin.

However, with the now known methods of carrying out these crimping operations the bond which is effected thereby has been of such character as not to withstand service usage and maintain, at the same time, a good mechanical bond and the required conductive connection between 40 the terminal and the conductor.

45 The manufacturers of motor vehicles have found it to be necessary to supplement the now known methods of crimping by soldering operations, in order to provide such a connection between the terminals and the conductors which will stand up satisfactorily over prolonged periods of service usage. However, this supplemental soldering is extremely undesirable from the aspect of increased cost.

50 With the foregoing conditions in mind this invention has in view, as its foremost objective, the provision of a terminal which is crimped to a conductor in such a manner as to provide at the same time a highly effective mechanical bond, and a good conductive connection, both of which

elements are maintained during prolonged periods of service usage without being supplemented by any soldering or other processes.

5 The insulated electrical conductors of the type with which this invention is primarily concerned, and which are meeting with widespread use in the automotive field, consist of the conductor proper defined by a plurality of strands which are twisted in a well-known manner and which are covered by the insulation. The insulation is stripped back from the end of each conductor a required distance to provide for the mounting of the terminal thereon. The terminals ordinarily comprise a nose and neck through which extend a cylindrical bore which is adapted to receive the stranded conductor, and a skirt having an enlarged bore which receives the insulation.

10 In order to render practical the assembling of the terminals on the conductors it is necessary that the stranded conductor be readily inserted in the smaller bore extending through the nose and neck. As a general rule the conductor has a smaller diameter than the bore to permit of this required ready insertion. With the stranded conductor positioned in the bore it has been the 15 20 25 30 35 40 45 50

practice to crimp the terminal to the conductor by subjecting the terminal and conductor therewithin to the effects of deforming instrumentalities, such as radially moving crimping jaws which heretofore have served to decrease both the cross sectional area of the bore of the terminal as well as the contact surface between the bore and the conductor.

In carrying out the above noted objective this 35 40 45 50 55

35 invention contemplates a departure from this known practice by providing for a decrease in the cross sectional area of the bore at the zone of crimping, at the same time maintaining constant or increasing the contact surface between the conductor and the bore of the terminal.

40 The heretofore prevalent practice of crimping the terminal to the conductor by decreasing the cross sectional area of the bore of the terminal so as to crowd the strands of the conductor together, with a tendency to more or less fuse the same into a solid cross section, has also been characterized by a reduction in the maximum cross sectional dimension of the conductor. The present invention also contemplates a radical departure from this condition by providing for an increase in the maximum cross sectional dimension of the stranded conductor over its original diameter, rather than any decrease, thus providing for enlargements of portions of the con- 50 55

ductor within the bore of the terminal, which afford a good mechanical bond.

An important part of my invention is the discovery that this desired action on the part of the metal of the terminal and the conductor may be obtained by crimping the terminal at exactly three points equi-angularly spaced about the terminal, the crimpings being formed by radially moving jaws in a manner well-known in this art.

10 The invention, therefore, has in view, as an important object, the provision of a terminal which is crimped to an electrical conductor at exactly three points equi-angularly spaced thereabout.

15 In view of the use to which the terminal is to be put, namely the insertion thereof into a socket to establish a detachable connection, it is important that the terminal maintain substantially its original formation after crimping operations, 20 and the invention, therefore, has in view, as a further objective, the provision of a terminal which is crimped to an electrical conductor and which maintains substantially its original circular formation at the zone of crimping. This objective 25 is maintained by deforming only substantially 50 per cent of the circumferential extent of the terminal at the zone of crimping.

It is evident that if the reduction of the cross sectional area of the terminal at the zone of 30 crimping is carried too far the conductor will be substantially severed, or so weakened as to be unable to stand any appreciable stress. There is, therefore, a limit to which this reduction in cross sectional area may be carried.

35 Recognizing that under certain conditions the attainment of this limit will still not provide a mechanical bond of such character as will withstand service usage, the invention has in view, as a further objective, the provision of a terminal 40 which is crimped to an electrical conductor at spaced zones. Thus the mechanical bond at one zone is supplemented by the bond at another zone, and a still further benefit is obtained by the interaction of the crimpings at the two zones. The 45 formation of the crimpings at any one zone of necessity creates a certain amount of longitudinal flow in the metal, and the longitudinal flow from one zone cooperates with the opposite flow from the other zone in such a manner as to provide for 50 a thoroughly effective bond and good conductive connection between the terminal and the conductor.

The invention has in view, as a further objective, the provision of a terminal including a 55 nose, and a neck through which extends a cylindrical bore that receives an electrical conductor, with the terminal being crimped to the conductor at one zone which is located substantially at the extremity of the nose, and at another zone which 60 is located at the neck.

Due to the fact that the reduction of cross sectional area of the electrical conductor at the extremity of the nose is not of so much importance it has been found entirely practical to increase 65 the number of crimpings at the zone in the nose.

Accordingly, the invention has in view, as a further objective, the provision of an electrical terminal which is mounted on a conductor in the manner above described, and in which there are 70 a larger number of crimpings in the nose than in the neck, and still more in detail a further objective is the provision of an arrangement in which the number of crimpings in the nose is substantially twice the number of crimpings in 75 the neck.

These and various other detailed objects and advantages such as arise in connection with carrying out the above noted thoughts in a practical embodiment will in part become apparent, and in part be hereinafter stated, as the description of the invention proceeds.

The invention, therefore, comprises an electrical terminal including a nose and neck through which extends a cylindrical bore that receives the stripped extremity of an insulated electrical conductor, the terminal being deformed at its neck by three crimpings equi-angularly spaced about the terminal to decrease the cross sectional area of the bore thereof, at the same time increasing the surface contact between the bore of the terminal and the conductor, the metal of the terminal also being crimped to the conductor at a zone substantially at the extremity of the nose, there being twice as many crimps in the nose as in the neck.

20 For a full and more complete understanding of the invention reference may be had to the following description and accompanying drawings, wherein

Figure 1 is a side view partly in section and partly in elevation, showing a terminal applied to an electrical conductor prior to the crimping thereto.

Figure 2 is a side view somewhat similar to Figure 1, but showing a terminal in elevation, 30

Figure 3 is another side elevational showing developing the terminal after the crimping operations have been carried out,

Figure 4 is an end elevational showing taken about on the plane represented by the line 4—4 35 of Figure 3,

Figure 5 is a cross section taken about on the plane represented by the line 5—5 of Figure 3, and

Figure 6 is another cross section taken about 40 on the plane represented by the line 6—6 of Figure 3.

Referring now to the drawing, wherein like reference characters denote corresponding parts, an insulated electrical conductor of the type 45 with which this invention is concerned is referred to in its entirety by the reference character A, and is shown as comprising a stranded metallic conductor 10 which is covered by insulation 11 in a well-known manner.

50 At this point it is well to note that the invention is primarily concerned with a stranded conductor of the type illustrated, as it is such conductors as these which are meeting with widespread use in the automotive field. However, the 55 invention is not to be strictly limited in this respect as it is susceptible of being utilized to great advantage with solid conductors. It will be noted that the insulation 11 is stripped back from the extremity of the conductor 10, leaving the section 60 at the end thereof bare.

A terminal is referred to in its entirety by the reference character B, and is made from a good conductive metal as is well known to those skilled in this art. This terminal B ordinarily includes 65 a nose-like end portion designated 12, and a skirt 13 which fits over the insulation 11. Between the nose 12 and skirt 13 is a neck 14 which may include a groove 15 that functions to establish the detachable connection with the socket in which 70 the terminal is inserted. Extending throughout the nose 12 and neck 14 is a bore 16 which is enlarged in the skirt 13, as shown at 17.

Following the usual practice in this art the conductor 10 will have a diameter appreciably 75

smaller than the bore 16 so as to permit of the ready insertion of the conductor in the bore. With the stranded conductor 10 fitted in the bore 16, and the insulation 11 in the bore 17 of the skirt 13, as depicted in Figure 1, a suitable crimping machine, such as that illustrated and described in the patent to White, No. 2,114,159, may be availed of to simultaneously crimp the terminal to the conductor at zones located in the nose 12 and neck 14 respectively, and also to crimp the skirt 13 to the insulation 11.

Referring more particularly to Figures 3 and 5, it will be noted that the crimps in the neck 14 are three in number, and designated 18. These crimps 18 are equi-angularly spaced apart about the neck 14 and are so dimensioned as to leave substantially undisturbed 50 per cent of the circumferential extent of the neck 14. The formation of these crimps 18 in the wall of the neck 14 about the conductor 10 involves a folding of the metal, such as depicted in Figure 5. This folding of the metal, while it is effective to diminish the cross sectional area defined by the bore 16 still maintains constant, or, as is more usually the case, increases the periphery now defined by the wall of the terminal.

Thus while there is a crowding of the strands of the conductor 10 to fuse the same into a substantially solid mass, the contact surface between the conductor 10 and the inner wall of the neck 14 remains at least substantially constant, or is increased, which is the usual case. It is also important to note that the points designated 19, which were originally on the bore 16 of the neck 14, move inwardly a maximum distance, while other points such as designated 20 remain substantially stationary or perhaps move slightly outwardly.

Extending between the points 19 and 20 are surfaces identified at 21, and this inner movement of the points 19 causes the strands of the conductor 10 to be squeezed between the surfaces 21, and this squeezing action is particularly enhanced closely adjacent to the points 20 due to 45 well-known physical rules of mechanical advantage.

It is also notable that the circular formation originally assumed by the stranded conductor 10 has been materially changed and that the cross section of the stranded conductor which is shown in Figure 5 presents a maximum dimension which is in excess of the original diameter of the stranded conductor 10. This change in the shape of the metallic structure of the conductor 10 presents a structure comparable to a riveted joint in that the deformed portion within the crimps 18 of the neck 14 are constituted the equivalent of a riveted end.

Referring now more particularly to Figures 3 and 4, it will be noted that the metal of the terminal at the extremity of the nose 12 is deformed by a plurality of crimps designated 22, which, in the illustrated embodiment, are six in number. There is a certain definite relationship between the presence and number of the crimps 22 in the nose 12 and the crimps 18 in the neck 14.

In the first place, the formation of the crimps 18 in the neck 14 is attended by a limit to which the cross sectional area defined by the wall of the bore 16 may be reduced, as a reduction past this limit would either sever the stranded structure 10, or so weaken the same as to render it incapable of withstanding any appreciable stress. However, this condition is not present in form-

ing the crimps 22 at the end of the nose 12. Moreover it is notable that it is the nose 12 which is originally inserted in the socket, and the shape of this nose must be maintained in order that the terminal be properly usable.

The formation of a large number of crimps 22 while providing for an effective connection at this zone still leaves undisturbed the shape of the nose. This deformation of the metal of the stranded conductor 10 involves a certain, though small, amount of longitudinal flow of the metal, and this longitudinal flow cooperates with a longitudinal flow in an opposite direction that is set up by the formation of the crimps 18, whereby the mechanical bond and conductive connection afforded at each zone of crimping is greatly enhanced.

As shown in Figures 3 and 6, still another series of crimps designated 23 may be formed in the skirt 13, and these crimps serve to crimp this skirt 13 to the insulation 11.

While a preferred specific embodiment of the invention is hereinbefore set forth it is to be clearly understood that I am not to be limited to the exact construction illustrated and described, because various modifications of these details may be provided in putting the invention into practice within the purview of the appended claims.

I claim:

1. An electrical connection, including members united in swaged relation; said members comprising insulated metallic conductor means and a grooved sleeve in which a bare end of said conductor means is disposed; a skirt provided on 35 said sleeve receiving the insulation in a manner to provide an annular space between the skirt and the insulation; said conductor means and said sleeve being swaged into a solid-metal cross-section in a predetermined transverse general 40 plane on one side of said groove; said conductor means and said sleeve also being swaged into a continuous solid-metal cross-section in a predetermined transverse general plane on the other side of said groove; and said skirt being crimped 45 to bring the sleeve and insulation on the conductor into bearing relation whereby to close said annular space and seal from the atmosphere at least one of said swaging planes.

2. The combination of an electrical fitting with 50 a metallic electrical conductor, comprising a metallic sleeve having two longitudinally aligned bores of different transverse dimensions and external means adapted to cooperate with a holding member of a sliding friction-type connector, 55 a metallic electrical conductor carrying insulation through part of its length and exposing a bare portion and having the bare portion of said electrical conductor arranged in the smaller of said bores of said sleeve and the insulated portion inserted in the larger of said bores of said sleeve, a plurality of longitudinally spaced crimpings formed in said sleeve and metallic conductor to join said sleeve and conductor and swage the metal of said sleeve and conductor into a continuous solid metal cross-section at the location of said crimpings, and crimpings formed in said sleeve and insulation carried by said metallic electrical conductor so as to grip said insulation tightly and seal the space between one of said crimpings between said sleeve and said metallic electrical conductor and the crimpings between said sleeve and said insulation.

JESSE M. WHITE.
